CLAIM

The ornamental design for a note holder, as shown and described.

DESCRIPTION

FIG. 1 is a front elevational view of the note holder of this invention;

FIG. 2 is a rear elevational view thereof;

FIG. 3 is a left-hand side elevational view thereof;

FIG. 4 is a right-hand side elevational view thereof;

FIG. 5 is a top plan view thereof;

FIG. 6 is a bottom plan view thereof;

FIG. 7 is a perspective view thereof; and,

FIG. 8 is a top plan view of the note holder with a piece of paper depicted by means of broken lines shown for illustrative purposes only and forming no part of the claimed design.
